UNITED STATES PATENT OFFICE.

CHARLES W. ROBISON, OF ALLEGHENY, PENNSYLVANIA.

DESIGN FOR A LOCK-KEEPER.

SPECIFICATION forming part of Design No. 16,410, dated December 8, 1885.

Application filed October 29, 1885. Serial No. 181,336. Term of patent 14 years.

To all whom it may concern:

Be it known that I, CHARLES W. ROBISON, of Allegheny city, in the county of Allegheny and State of Pennsylvania, have invented a new and useful Improvement in Design for Lock-Keepers; and I do hereby declare the following to be a full, clear, and exact description thereof.

My invention relates to a new design or aesthetical configuration for the combined lock-case and keeper of exposed or rim locks or latches; and it consists in the keeper having at the outer corners recesses which extend down to the base-plate or screw-plate thereof on regular lines, and its exterior or base lines continued in substantially the lines of the lock-case; or, in other words, the box of the keeper is of a length equal to the width of the lock-case, so as to produce the general effect of the form or pattern shown in the drawings accompanying this description.

In the drawings, Figure 1 is a plan view of a combined keeper and lock-case illustrating my design. Fig. 2 is a perspective view of the keeper, and Fig. 3 is a bottom plan view of the keeper.

In the class of locks or latches the keeper complements the lock-case, and as both are exposed in juxtaposition when the door is closed, there should be unity in design.

In the drawings, *a* indicates the keeper, and *b* the lock-case. The lock-case *b*, which is the usual rectangular figure, is supplemented by the keeper *a*. The length of the keeper *a*,

however, must be equal to the breadth of the lock-case *b*, so that when they are in position on a closed door the lock case and keeper may be coextensive, or, in other words, the keeper will continue the parallel side lines of the case *b*. The base or screw plate *d* of the keeper, which is integral with the box, preserves the rectangular form to correspond with the finish of the lock-case, while the box of the keeper sinks in or is recessed at the corners, as at *c c*, and thus a light and graceful finish is given to the keeper without destroying the quadrilateral or polygonal form of the combined lock-case and keeper. There are screw holes in the base-plate *d* at the corners, where the box of the keeper recedes from the parallel lines of the base.

Having thus described my design, what I claim is—

As a design for lock-case and keeper of latches and rim-locks, the configuration consisting of two parallelograms, the length of one being equal to the width of the other, and the lesser having recesses at its two outer corners, which recesses extend down to the base-plate, substantially as herein described and shown.

In testimony whereof I have hereunto set my hand this 24th day of October, A. D. 1885.

CHARLES W. ROBISON.
